(57) CLAIM

The ornamental design for a spare tire carrier assembly, as shown and described.

DESCRIPTION

FIG. 1 is a perspective view of a spare tire carrier assembly.

FIG. 2 is a front view of the design in FIG. 1.

FIG. 3 is a back view of the design in FIG. 1.

FIG. 4 is a left side view of the design in FIG. 1.

FIG. 5 is a right side view of the design in FIG. 1.

FIG. 6 is a top view of the design in FIG. 1.

FIG. 7 is a bottom view of the design in FIG. 1.

FIG. 8 is a perspective view of a spare tire carrier assembly, showing a second embodiment.

FIG. 9 is a front view of the design in FIG. 8.

FIG. 10 is a back view of the design in FIG. 8.

FIG. 11 is a left side view of the design in FIG. 8.

FIG. 12 is a right side view of the design in FIG. 8.

FIG. 13 is a top view of the design in FIG. 8; and,

FIG. 14 is a bottom view of the design in FIG. 8.
